UNITED STATES PATENT OFFICE.

SCOVILL S. ATKINS, OF YALESVILLE, CONNECTICUT, ASSIGNOR TO WILLIAM A. KENDRICK, OF YALESVILLE, CONNECTICUT.

DRAWING-KNIFE.

SPECIFICATION forming part of Letters Patent No. 690,222, dated December 31, 1901.

Application filed May 6, 1901. Serial No. 58,932. (No model.)

To all whom it may concern:

Be it known that I, SCOVILL S. ATKINS, a citizen of the United States, residing at Yalesville, in the county of New Haven and State of Connecticut, have invented certain new and useful Improvements in Drawing-Knives; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to drawing-knives; and it has for its object to provide an improved construction for attaching the handles to the shanks of the drawing-knife blade whereby the handles can be readily adjusted 20 to various positions and be securely held in whatever position to which they may be adjusted.

To the accomplishment of the foregoing and such other objects as may hereinafter appear, the invention consists in the construction and 25 in the combination of parts hereinafter particularly described, and then sought to be clearly defined by the claims, reference being had to the accompanying drawings, forming 30 ing a part hereof, and in which—

Figure 1 is a side view of the drawing-knife, showing one of the handles adjusted to a position parallel with and in front of the blade and the other handle standing at right angles thereto, the dotted lines indicating a third 35 position to which the handles may be adjusted. Fig. 2 is a section on the line $x-x$ of Fig. 1. Fig. 3 is a side view of a portion of one of the shanks with the handle applied in one 40 position; and Fig. 4 is a side view of a portion of one of the shanks, showing the ear at its end formed with the recesses to receive a part of the handle and the clamping-bolt, Figs. 2, 3, and 4 being full size.

45 In the drawings the numeral 1 designates the drawing-knife blade, and 2 the shanks thereof, which are curved forwardly, and each of which is formed at its end with an ear 3. Each ear is formed with an aperture 4 to receive 50 the clamping-bolt, said ear being also

formed in front of the opening 4 with a groove or recess 5 to receive a portion of the shank of the handle and at a point opposite to the recess 5 with another recess 6 to receive a part of the handle-shank and with a socket 7 55 to receive the bent or inturned end of the handle-shank when the handle is in position to extend forwardly and at right angles to the drawing-knife blade. Each ear is also formed with recesses 8 opposite to each other 60 at opposite sides of the opening 4 in the ear, which recesses will receive the handle-shank when the handle is turned inwardly parallel with and in front of the drawing-knife blade, as indicated by full lines in Fig. 1 of the 65 drawings, and also when the handle is turned outwardly and parallel with the drawing-knife blade, as indicated by dotted lines in Fig. 1 of the drawings. Each of the recesses 8 terminates at its outer end in a concave portion 70 9, which is designed to receive the bent or inturned end of the shank of the handle when in either of the two positions last mentioned, said concave portions serving as sockets for such inturned end of the shank, and thus assisting 75 in preventing the handles from turning and also from slipping out of the eye of the clamping-bolt when the nut on the same is loosened, and the recesses formed in the face of the ears will tend to prevent lateral 80 movement of the handles and assist in insuring the tight clamping of the handles to the shanks of the drawing-knife blade.

The handles are designated by the numeral 10, each handle having a rod 11 passed longitudinally through the same, one end of which is upset against a metal washer 12, set into the outer end of the handle, the opposite end of the rod projecting beyond the inner end of the handle, so as to form a shank to the 90 handle which will lie in some one of the recesses formed in the ears of the shanks to the drawing-knife blade, as before indicated, the extreme end of the rod being turned or bent inwardly, so as to form a stud or projection 95 13, which will lie within one of the sockets previously described. Upon the shank portion of the handle is mounted a clamping-bolt 14, through the head of which is formed a lateral opening designed to receive the shank 100

portion of the handle, said opening forming an eyebolt of this clamping-bolt. The threaded portion of the clamping-bolt passes through the opening 4, formed in each ear of the 5 drawing-blade shank, and has a thumb-nut 15 applied thereto, which will serve to clamp the handle to the shank of the drawing-knife blade when the nut is tightened, a washer 16 being interposed between the thumb-nut and 10 the ear of the drawing-knife blade, as indicated clearly in Fig. 2 of the drawings. The stud or projection 13 at the end of the handle-shank also serves to prevent the eyebolt from slipping off the shank when the parts 15 are loosened for the purpose of changing the position of the handles. When the handles are to be adjusted, the nut on the clamping-eyebolt is loosened and the handle turned or shifted, so as to bring the shank portion in 20 the desired recess in the ear of the shank to the drawing-knife blade, and then the nut is tightened so as to firmly and securely clamp the handle in its adjusted position. Each handle will be provided with a metal ferrule 25 17 at the end next to the projecting shank portion of the handle.

A drawing-knife constructed as described can have its handles easily and quickly adjusted to any of the various positions before 30 indicated, and when adjusted the handles will be securely clamped in place and held against movement in any direction by the clamping means described. The parts are simple in construction, not liable to get out 35 of working order, and admit of easy and quick manipulation of the same.

I have described with particularity what I consider to be the preferred details of construction and arrangement of the several 40 parts; but it is obvious that changes can be made in such details and essential features of my invention still be retained.

Having described my invention and set forth its merits, what I claim is—

1. In an edge-tool, the combination with 45 the tool-blade having a shank formed with an opening through it and having recesses formed in its face, of an adjustable handle having a shank to fit in the recesses of the blade-shank, an eyebolt passing through the 50 opening in the blade-shank and having the shank of the handle passed through its eye, and a nut applied to the eyebolt to clamp the parts together, substantially as described.

2. In an edge-tool, the combination with 55 the tool-blade having a shank formed with an opening through it and having recesses formed in its face and provided with sockets at the edge of some of the recesses, of an adjustable handle having a shank to fit in the 60 recesses of the blade-shank and a stud or projection to fit in the socket of the same, an eyebolt passing through the opening in the blade-shank and having the shank of the handle passed through its eye, and a nut applied to 65 the eyebolt for clamping the parts together, substantially as described.

3. In an edge-tool, the combination with 70 a tool-blade having a shank formed with an opening through it and also formed with a socket, of an adjustable handle having a shank provided with a stud or projection to fit in the socket of the blade-shank, an eyebolt passing through the opening in the blade-shank and having the shank of the handle 75 passed through its eye, and a nut applied to the eyebolt for clamping the parts together, substantially as described.

In testimony whereof I affix my signature in presence of two witnesses.

SCOVILL S. ATKINS.
